UNITED STATES PATENT OFFICE.

WILLIAM C. TYLER, OF RACINE, WISCONSIN, ASSIGNOR TO AJAX RUBBER COMPANY, INC., OF RACINE, WISCONSIN, A CORPORATION OF NEW YORK.

DESIGN FOR A TIRE.

Application filed November 9, 1928. Serial No. 28,818. Term of patent 14 years.

To all whom it may concern:

Be it known that I, WILLIAM C. TYLER, a citizen of the United States, residing at Racine, in the county of Racine and State of Wisconsin, have invented a new, original, and ornamental Design for Tires, of which the following is a specification, reference being had to the accompanying drawings, forming a part thereof.

Fig. 1 is a plan view of a section of a tire showing my new design.

Fig. 2 is a side elevation of the section of a tire shown in Fig. 1.

Fig. 3 is a transverse sectional view on the line 3—3 of Fig. 1.

I claim:

The ornamental design for a tire, as shown.

WILLIAM C. TYLER.
